[57] CLAIM

The ornamental design for a biscuit cutter, as shown and described.

DESCRIPTION

FIG. 1 is a top, front, and left side perspective view of a biscuit cutter showing my new design;

FIG. 2 is a bottom, rear, and right side perspective view thereof;

FIG. 3 is a top, front, and right side perspective view of the cutter blade shown separately for clarity of illustration, the rear and left side being a mirror image; and FIG. 4 is a sectional view taken along lines 4—4 of FIG. 3.

FIG. I.

FIG. 2

FIG. 4
